US00D652302S

(12) **United States Design Patent**
Drake et al.

(10) **Patent No.:** **US D652,302 S**
(45) **Date of Patent:** **** Jan. 17, 2012**

(54) **BOTTLE**

(75) Inventors: **Paul Lee Drake**, Turnbridge Wells (GB); **Timothy Hope Jebb**, Turnbridge Wells (GB); **Benjamin James Lambert**, Turnbridge Wells (GB); **Philip Alan Marlow**, Turnbridge Wells (GB); **Benjamin Phalan Oates**, Turnbridge Wells (GB)

(73) Assignee: **Conopco, Inc.**, Englewood Cliffs, NJ (US)

(**) Term: **14 Years**

(21) Appl. No.: **29/363,714**

(22) Filed: **Jun. 14, 2010**

(30) **Foreign Application Priority Data**

Dec. 14, 2009 (GB) 4013750

(51) **LOC (9) Cl.** **09-01**

(52) **U.S. Cl.** **D9/521**; D9/529; D9/447; D9/449

(58) **Field of Classification Search** D9/516, D9/521–522, 529–530, 537–543, 552, 561, D9/565, 574–575; 215/382–384; 220/660, 220/669, 675

See application file for complete search history.
